UNITED STATES PATENT OFFICE.

GEORGE R. WADSWORTH, OF CLEVELAND, OHIO, ASSIGNOR TO THE PEERLESS MOTOR CAR COMPANY, OF CLEVELAND, OHIO, A CORPORATION OF OHIO.

DESIGN FOR A LAMP.

44,621.

Specification for Design.

Patented Sept. 2, 1913.

Application filed May 26, 1913. Serial No. 770,079. Term of patent 7 years.

To all whom it may concern:

Be it known that I, GEORGE R. WADSWORTH, a citizen of the United States, residing at Cleveland, in the county of Cuyahoga and State of Ohio, have invented a new, original, and ornamental Design for Lamps, of which the following is a specification, reference being had to the accompanying drawing, forming part hereof.

In the drawing, Figure 1 is a side eleva-

tion, and Fig. 2 is a plan view of a lamp, showing my new design.

I claim:

The ornamental design for a lamp, as shown.

GEORGE R. WADSWORTH.

Witnesses:

A. F. KWIS,

L. I. PORTER.
